UNITED STATES PATENT OFFICE.

ALWIN VON AUW, OF BROOKLYN, NEW YORK, ASSIGNOR TO BOORUM AND PEASE COMPANY, OF NEW YORK, N. Y., A CORPORATION OF NEW YORK.

APPARATUS FOR USE IN THE MANUFACTURE OF BOOKS.

1,250,728.

Specification of Letters Patent. Patented Dec. 18, 1917.

Application filed June 29, 1914. Serial No. 847,988.

To all whom it may concern:

Be it known that I, ALWIN VON AUW, a citizen of the United States of America, and residing in the borough of Brooklyn, in the county of Kings and State of New York, have invented a certain new and useful Apparatus for Use in the Manufacture of Books, of which the following is a specification.

10 My invention relates to apparatus for use in the manufacture of books and particularly to apparatus for applying hinge tape and filler strips to sheets for ledgers and the like. The sheets thus prepared are particularly 15 useful in the manufacture of loose leaf account books, journals, etc.

In the accompanying drawings,

Figure 1 is a side elevation of so much of a machine as is necessary to illustrate the 20 embodiment of my invention therein;

Fig. 1^a is a continuation of the right hand end of Fig. 1, showing the piling table.

Fig. 2 is a horizontal section on the line 2—2, Fig. 1;

25 Fig. 3 is a diagrammatic side elevation showing the manner of application of the hinge and filler elements to the sheets as they pass through the machine;

Fig. 4 is a diagrammatic section of the 30 same;

Fig. 5 is an enlarged view of the cutter;

Fig. 6 is a partial side elevation of the latter;

35 Fig. 7 is a perspective of paste-applying roller; and

Fig. 8 is a perspective of portion of the pressure drum showing its end recessed to receive a heater.

Fig. 9 is a broken end view of a book comprising leaves made by the present machine.

The book, in the manufacture of which the present apparatus is specially designed for use, is of the general type illustrated in the patent to Griesenger 881,794. Its leaves 45 comprise paper sheets of different widths, hinge strips preferably of fabric and of correspondingly different widths so that the pages which comprise the assembled sheets and hinge strips are of uniform size; and, 50 when necessary, filler strips on the hinge strips to insure substantial uniformity of thickness in the stub and in the body of the book.

Broadly speaking, the machine comprises a plurality of supports for sheets of different widths, a plurality of carriers for reels of hinge tape of different widths, one or more carriers for filler strips, means for suitably applying adhesive, means for assembling the sheets, hinge tapes and filler strips, means for severing the hinge tape and filler strips beyond the end of the sheets, and means for delivering the several assembled sheets in superposed relation.

To this end the apparatus comprises a 65 frame having uprights 10, 11 and 12 with a plurality, here three, tiers of stringers 13, 14 and 15, on which are journaled the various rollers 16 for the traveling tapes or strings by which the sheets X are carried through 70 the machine. For each tier, a reel 17 of hinge tape 18 is provided, the tapes being of different width and in each case being led from its reel at one end of the frame over a paste-applying roller 19 to a straightening 75 edge 20 and guide roller 21 at the other end of the machine, so that during the passage of the tape from one end of the frame to the other, the paste has opportunity to become somewhat dry and "tacky."

80 Accurately positioned with relation to each roller 21 is a guide plate 22 against which the edge of a sheet X carried by strings a is held by guards 23, so that the tape 18 rising to the roller 16^a slightly overlaps the edge of the ledger sheet X and adheres thereto. Both tape and sheet are nipped between the roller 16^b and drum 24 and pass over the latter under pressure beneath the strings b stretched between rollers 16^b and 16^c. Strings c receive the sheet with tape attached on delivery from roller 16^c and a cutting device 25, of any suitable sort, 85 severs the hinge tape beyond the edge of the sheet. The cutters here shown are driven 90 from a main shaft 26 and each comprises a reciprocating blade the operation of which is electrically controlled through a pair of contacts 27^a, 27^b separated by the passage of the sheet between the same and closing automatically after the end of the sheet has passed. The mechanism is not explained in detail since it is of known type and its details form no part of my invention.

100 The sheet with its length of hinge tape 105 attached is discharged to the strings d and

by the latter is carried to the common conveyer *e* upon which the several strings *d* converge. If the feed of sheets to the strings *a* is properly regulated, they are superposed substantially in register upon their discharge to the conveyer *e* and are carried by the latter in proper relation for the binder, to a piling table *f* of common type. The strings *d* for the upper and lower tiers may be made to travel faster than those for the middle tier, in order to take up the slightly greater distance of travel to the conveyer *e*.

Since as above explained, the hinge tapes are of different widths for the different tiers, it is desirable to use ledger sheets of different widths. The leaves formed of the combined sheets and tapes are thus of uniform dimensions and the necessity for subsequent trimming of the sheets is thus avoided. If the outer sides of the guide rollers 21 for the several tiers are in vertical alinement, the inner faces of the rollers, which are of different widths corresponding to the widths of the tape are therefore stepped inwardly (Fig. 4). The guide plates 22 are correspondingly stepped inwardly. On the other hand the distance between the guards 23 and the outer faces of the guide rollers 21 is uniform since the sheets *X* decrease in width in proportion to the increase in width of the hinge tape.

As explained in the patent above mentioned it is desirable to provide fillers for the stub of the hook in order to secure substantially uniform thickness in both the stub and the body of the book. Filler strips 28 are employed for this purpose and they may be applied to one or more of the hinge tapes as required by the thickness of the ledger sheet and hinge tape. As here shown, a reel 29 for the filler strip 28 is provided for each tier so that it may be used on any sheet. But it is to be understood that under ordinary conditions, the filler strip will be applied only to the sheets in one or two of the tiers. The filler strip is carried up from the reel over rollers 30 and 31 and down to the hinge strip as it enters the nip between rollers 16^b and drum 24. The roller 31 feeds the filler strip to the same face of the hinge strip as the ledger sheet, but the roller is so positioned that the filler strip is spaced from the edge of the ledger sheet in order not to impair the flexibility of the hinge strip. If the outer faces of guide rollers 21 for the hinge tape are alined as above suggested, the outer faces of the guide rollers 31 for the filler strip will preferably be substantially alined therewith, so that the outer edge of the filler strip lies substantially flush with that of the hinge strip. A uniform flat back for the book is thus afforded.

65 Inasmuch as the flexibility of the hinge

tape should be interfered with as little as possible, and there should be no adhesion between the hinges of adjacent strips, care must be taken to supply adhesive only to those portions of the tape which are in contact with the ledger sheet at one side and the stub strip on the other side of those sheets to which a filler strip is attached. The pasting roller, in the latter case, is therefore provided with two contact surfaces 32-33 spaced apart, as for instance by a peripheral groove 34, when the roller is solid, or by two disks spaced apart on a common axis. To prevent an excess of adhesive being carried up to the tape, a scraper 35 is preferably used, having scraping edges for the two contact surfaces 32, 33 of the pasting roller and a tongue 36 which keeps clean the groove or space between the same. For those sheets which are not supplied with filler strips, a disk with single contact surface is provided, and so located with relation to the hinge tape that it contacts with that portion only thereof which overlaps the ledger sheet.

The sheets may be of requisite size for any desired size or shape of book, since the guards 23 are adjustable to accommodate sheets of different width. The cut-off mechanism for the hinge tapes operates irrespective of the length of the sheets. The number of tiers may be as many as desired, three being sufficient under ordinary circumstances to accomplish the desired purpose. Presser rollers 37 may be arranged to bear upon the tape at a point just beyond the cut-off. Where the hinge tape is very heavy this roller may be necessary to hold the tape during the action of the cutting knife; but under ordinary circumstances it is unnecessary. It has some value in assisting the feed, by reason of the fact that it presses the tape heavily against one of the drawing rollers. But this assistance is unnecessary since the tape is carried forward by the sheet to which it is attached. Again, the end of the drum 24 may be recessed to afford room for a heating device, (Fig. 7) by means of which the drum serves the function of a drying as well as a pressure drum. But if the paste is of proper consistency and the scrapers are properly adjusted, that applied to the hinge tape has become "tacky" by the time it reaches the drum, and a heater or drier is not needed.

The particular arrangement and construction of the various details of the machine may be readily varied while securing substantially similar results, and I do not limit my invention to the precise structure shown and described.

I claim as my invention:

1. In apparatus of the type described, means for supporting a plurality of sheets of different widths and means for applying

in overlapped position at the edges thereof hinge tapes of different widths to produce combined sheets and hinge tapes forming leaves of uniform width.

5 2. In apparatus of the type described, means for supporting a plurality of sheets of different widths and means for applying in overlapped position at the edges thereof hinge tapes of different widths to produce 10 combined sheets and hinge tapes forming leaves of uniform width, together with means for delivering said leaves in superposed position.

3. In apparatus of the type described, 15 means for supporting a plurality of sheets of different widths, means for applying in overlapped position at the edges thereof continuous lengths of hinge tapes of different widths to produce leaves of uniform width, and means for cutting said tapes beyond the ends of the several sheets.

4. In apparatus of the type described, 20 means for supporting a plurality of sheets of different widths, means for applying in overlapped position at the edges thereof continuous lengths of hinge tapes of different widths to produce leaves of uniform width, and means for cutting said tapes beyond the ends of the several sheets, together with 25 means for delivering said leaves in superposed position.

5. In apparatus of the type described, 30 means for traveling a plurality of independent sheets, means for applying during their travel and in overlapped position at the edges on one side thereof continuous hinge tapes of different widths, one to each sheet, and means for cutting said tapes beyond the ends of the several sheets together with 35 means for delivering said taped sheets in superposed position.

6. In apparatus of the type described, 40 means for simultaneously traveling a plurality of independent sheets of different widths, means for applying thereto respectively during their travel and in overlapped position at the edges at one side thereof, continuous hinge tapes of different widths to form leaves of uniform width and means 45 for cutting said tapes beyond the end of each sheet.

7. In apparatus of the type described, 50 means for simultaneously traveling a plurality of independent sheets of different widths, means for applying thereto respectively during their travel and in overlapped position at the edges at one side thereof, continuous hinge tapes of different widths to form leaves of uniform width and means 55 for cutting said tapes beyond the end of each sheet, together with means for delivering said leaves in superposed position.

8. In apparatus of the type described, 60 means for supporting a sheet of paper and a filler strip with their adjacent edges spaced

apart, and means for applying thereto a hinge tape in overlapped relation to both the sheet and the filler strip, said tape completely overlapping the filler strip but overlying only the edge of the sheet of paper, 70 substantially as described.

9. In apparatus of the type described, 75 means for supporting a sheet of paper and a continuous length of filler strip with their adjacent edges spaced apart, means for applying thereto a continuous length of hinge tape in overlapped relation to the said edges of both sheet and filler strip said tape completely overlapping the filler strip but overlying only the edge of the sheet of paper, 80 and means for cutting said lengths of filler strip and hinge tape beyond the end of the sheet.

10. In apparatus of the type described, 85 means for traveling a plurality of sheets of paper, means for supplying a continuous length of filler strip with its adjacent edge spaced from said sheets, and means for applying during their travel and in overlapped relation to the said edges of said filler strip 90 and sheets continuous lengths of hinge tape, and means for cutting said tape and filler strip beyond the edges of each sheet.

11. In apparatus of the type described, 95 means for simultaneously supporting a plurality of sheets of different widths, means for applying to the edges thereof respectively hinge tapes of different widths to form leaves of uniform width, and means for applying filler strips to only certain of 100 said hinge tapes, with the edges of said filler strips and sheets spaced apart.

12. In apparatus of the type described, 105 means for supporting a sheet of paper, means for supplying a filler strip with its adjacent edge spaced from the edge of said sheet, means for applying a hinge tape in overlapped relation to said adjacent edges of sheet and filler strip and means for supplying adhesive only to the overlapping portions of said hinge tape. 110

13. In apparatus of the type described, 115 means for supporting a sheet of paper, means for supporting a filler strip with its adjacent edge spaced from the edge of said sheet, means for applying a hinge tape in overlapped relation to said adjacent edges of sheet and filler strip and means for supplying adhesive only to the overlapping portions of said hinge tape, said adhesive being 120 applied to said tape at a distance from the point of application of the tape to the sheet and filler strip to permit said adhesive to dry and become "tacky" before the application of the tape. 125

14. In apparatus of the type described, 130 means for supporting a sheet and a filler strip spaced apart, means for feeding thereto a length of hinge tape, means for applying adhesive only to the opposite edges of

one face thereof, and means for pressing said face to the adjacent spaced edges of a sheet and filler strip, for the purpose described.

15. In apparatus of the type described, means for supporting a sheet of paper and a filler strip with their adjacent edges spaced apart, and means for applying thereto a hinge tape in overlapped relation to both said sheet and filler strip, the back edge of said tape being substantially flush with the corresponding edge of the filler strip, for the purpose described.

16. In apparatus of the type described, means for supporting a plurality of sheets, means for applying in overlapped position at the edges thereof, hinge tapes of different widths for the respective sheets and means for assembling said sheets in a common pile in which adjacent sheets have hinge tapes of different width.

17. In apparatus of the type described, means for supporting a plurality of sheets, means for applying in overlapped position at the edge thereof continuous lengths of hinge tapes of different widths for the respective sheets, means for cutting said tapes at the edges of the several sheets, and means for assembling said sheets in a common pile in which adjacent sheets have hinge tapes of different width.

18. In apparatus of the type described, means for supporting a plurality of sheets, means for applying in overlapped position at the edges thereof, hinge tapes of different

widths for the respective sheets, means for applying a filler strip to the free margin of at least one of said hinge tapes.

19. In apparatus of the type described, means for supporting a plurality of sheets, means for applying in overlapped position at the edges thereof, hinge tapes of different widths for the respective sheets, means for applying a continuous length of filler strip to the free margin of at least one of said hinge tapes, means for cutting said filler strip at the edge of each sheet and means for assembling said sheets in a common pile in which adjacent sheets have hinge tapes of different width.

20. In apparatus of the type described, means for supporting a plurality of sheets, means for applying in overlapped position at the edges thereof continuous lengths of hinge tape of different widths for the respective sheets, means for applying to the free margin of at least one of said hinge tapes a continuous filler strip, means for cutting said hinge tapes and filler strip at the edges of the sheets, and means for assembling said sheets in a common pile in which adjacent sheets have hinge tapes of different width.

In testimony whereof I have signed my name to this specification, in the presence of two subscribing witnesses.

ALWIN VON AUW.
